(57) **CLAIM**

The ornamental design for a valve, as shown and described.

DESCRIPTION

FIG. 1 is a front view of my new valve design in open position;

FIG. 2 is a left end view thereof;

FIG. 3 is a right end view thereof;

FIG. 4 is a top view of the valve design, with the valve shown in the open position;

FIG. 5 is a sectional view showing two valve stops for the valve knob, but with the valve in the open position;

FIG. 6 is another top view, with the valve knob rotated 90°, but showing the valve in the closed position;

FIG. 7 is another sectional view showing the valve knob rotated 90° (closed position);

FIG. 8 is bottom view thereof, with the valve in open position; and,

FIG. 9 is a rear view thereof.
